The ornamental design for the disconnect tool for removing
quick connect plumbing fittings as shown and described.

DESCRIPTION

FIG. 1 is an upper isometric view of a disconnect tool for
removing quick connect plumbing fittings according to a
first embodiment.

FIG. 2 is a lower isometric view of the disconnect tool for
removing quick connect plumbing fittings.

FIG. 3 is a front view of the disconnect tool for removing
quick connect plumbing fittings.

FIG. 4 is a back view of the disconnect tool for removing
quick connect plumbing fittings.

FIG. 5 is a left view of the disconnect tool for removing
quick connect plumbing fittings.

FIG. 6 is a right view of the disconnect tool for removing
quick connect plumbing fittings.

FIG. 7 is a top view of the disconnect tool for removing
quick connect plumbing fittings.

FIG. 8 is a bottom view of the disconnect tool for removing
quick connect plumbing fittings.

FIG. 9 is an upper isometric view of a disconnect tool for
removing quick connect plumbing fittings according to a
second embodiment.

FIG. 10 is a lower isometric view of the disconnect tool for
removing quick connect plumbing fittings of FIG. 9.

FIG. 11 is a front view of the disconnect tool for removing
quick connect plumbing fittings of FIG. 9.

FIG. 12 is a back view of the disconnect tool for removing
quick connect plumbing fittings of FIG. 9.

FIG. 13 is a left view of the disconnect tool for removing
quick connect plumbing fittings of FIG. 9.

FIG. 14 is a right view of the disconnect tool for removing
quick connect plumbing fittings of FIG. 9.

FIG. 15 is a top view of the disconnect tool for removing
quick connect plumbing fittings of FIG. 9.

FIG. 16 is a bottom view of the disconnect tool for removing
quick connect plumbing fittings of FIG. 9.

FIG. 17 is an upper isometric view of a disconnect tool for
removing quick connect plumbing fittings according to a
third embodiment.

FIG. 18 is a lower isometric view of the disconnect tool for
removing quick connect plumbing fittings of FIG. 17.

FIG. 19 is a front view of the disconnect tool for removing
quick connect plumbing fittings of FIG. 17.

FIG. 20 is a back view of the disconnect tool for removing
quick connect plumbing fittings of FIG. 17.

FIG. 21 is a left view of the disconnect tool for removing
quick connect plumbing fittings of FIG. 17.

FIG. 22 is a right view of the disconnect tool for removing
quick connect plumbing fittings of FIG. 17.

(Continued)

FIG. 23 is a top view of the disconnect tool for removing quick connect plumbing fittings of FIG. 17; and, FIG. 24 is a bottom view of the disconnect tool for removing quick connect plumbing fittings of FIG. 17. The broken lines shown within the drawings are included for the purpose of illustrating portions of the disconnect tool for removing quick connect plumbing fittings that form no part of the claimed design. The dotted lines shown within the drawings are included for the purpose of illustrating boundaries between claimed and unclaimed portions of the design.
